UNITED STATES PATENT OFFICE.

EDGAR J. MARTEL, OF LACONIA, NEW HAMPSHIRE.

LOCKING DEVICE FOR AUTOMOBILES.

Application filed October 26, 1926. Serial No. 144,264.

This invention relates to apparatus for locking an automobile and stopping the engine by a single motion on the part of the operator, this application being a continuation of my co-pending application Serial No. 105,343, filed April 29, 1926 as to all subject matter common to both. An object of the invention is to lock the car in several respects so as to make it exceedingly difficult for a person not in possession of the proper key to operate the car. By my invention, all the devices for locking various parts are put into operation by one act such as that of turning a key in its lock. Further advantageous features and combinations will be apparent to one skilled in the art from the disclosures of my invention in the following description and on the drawing, of which:

Figure 1 indicates a portion of the mechanism of an automobile showing an embodiment of my invention applied thereto.

Figure 2 is a section on the line 2—2 of Figure 1.

Figure 3 is an elevation partly in section of another embodiment of my invention.

Figure 4 is a plan view of a portion of the apparatus shown in Figure 3.

Referring to the drawing in detail, the automobile mechanism illustrated in Figure 1 is of a conventional type common to many makes of cars and includes a main shaft 10 from the motor, a clutch mechanism generally indicated at 11, and transmission mechanism indicated at 12 which may be of any desired construction. As shown the transmission gears are shifted by a pair of shifter rods 13, 14 which are selectively engaged by a suitable knob 15 at the lower end of an operating lever 16, this construction being well known in the art. In order to lock the transmission mechanism in any desired position, neutral, reverse, or any speed forward, I form a pair of notches 17, 18 in the shifter rod 13 and corresponding notches 19, 20 in the shifter rod 14. As shown in Figure 4, the shifter rods are in neutral position and the notches 17, 18 are respectively opposite the notches 19, 20. The recess formed by the opposing notches 18, 20 is adapted to

receive an end 21 of a locking lever 22 which is pivotally mounted as at 23 to the housing of the transmission gear. The notches in the shifter rods 13 and 14 are so positioned that when the shifter rod 13 is shifted forward, the notch 17 will be opposite the notch 20. When this shifter rod is shifted rearwardly, the locking end 21 of the lever 22 will rest against the forward end of the rod 13 when it occupies the notch 20 in the rod 14. In like manner, when the shifter rod 14 is shifted, the notch 19 or the forward end of the rod will cooperate with the notch 18 to enable the locking end 21 to lock both rods in any position of operation. A compression spring 24 may be provided to press the lever 22 downwardly toward its locking position, although such a spring is not essential as the lever may be allowed to descend into locking position by gravity. I provide cam means to move the lever out of locking position against the force of gravity and the spring 24. This unlocking means comprises a vertically disposed shaft 25 on the lower end of which is fixed a disk or plate 26, the plane of which is inclined to the axis of the shaft 25. An edge of the disk 26 engages under a lug 27 formed on the lever 22. It is obvious that rotation of the shaft 25 will bring the high side of the disk 26 under the lug 27, thus raising the lever 22 and unlocking the transmission mechanism. At the upper end of the shaft 25 is fixed a cylinder or lock-barrel 28 which is provided with suitable plungers and springs as found in locking devices well known in the art. The cylinder 28 is journaled in the upper end of a column 29 which contains plungers 30 cooperating with those in the cylinder 28 and locking the cylinder 28 against rotation unless the proper key 31 is inserted. In Figure 3 this form of my mechanism is illustrated in locked position. In order to stop the motor when the transmission mechanism is locked, I mount a contact member 32 upon the shaft 25 to turn therewith. On either side of the path of the contact member 32, I place contact points 33, which points are preferably connected into the ignition circuit. The points

33 are so arranged with relation to the contact member 32 that when the shaft 25 is rotated to a position to lock the transmission, the contact member will be separated from the points 33, but when the shaft is rotated to unlock the transmission gears, the member 32 will bridge the gap between the points 33 and close that portion of the ignition circuit. As an additional safeguard, I provide a lock for the self-starter switch. The switch itself may be of any conventional type adapted to be closed by the depression of a suitable plunger 34. Into the path of this plunger, I interpose a rod or stop member 35 which is drawn inwardly as by a spring 36 and when in locking position prevents the depression of the plunger 34 to close the self-starter circuit. A suitable cable 37 connects the rod 35 with an ear 38 formed on the shaft 25. The ear 38 is so arranged that when the shaft 25 is rotated from locking position, as shown in Figure 3, to unlocked position, the ear will retract the rod 35 from the path of the plunger 34, and thus make it possible to use the self starter. It will be noticed that by this arrangement it is impossible to operate the self starter until the ignition switch has been closed since the rotation of the shaft 25 which unlocks the self-starter switch simultaneously closes the ignition switch 32, 33. This prevents wastage of battery current through an attempt to start the motor when the operator has forgotten to close the ignition switch.

In Figure 1 is shown a different embodiment of my invention, comprising a locking member 39 having a portion 40 at the upper end thereof sliding in a column 41. The lower end of this locking member 39 engages notches in the shifter rods as previously described to lock the transmission gear in any desired position. The member 39 is normally held in unlocked position as by a spring 42 which presses it upwardly. In order to lock the transmission gear, I provide a hand-operated plunger 43, the lower end of which rests on the top of the sliding portion 40 or is loosely inserted in a recess therein. In the upper portion of the column 41 a suitable lock 44 is mounted adapted to receive a key 45, the turning of which will retract a projection 46 which is positioned to engage a portion of the upper member 40 when it is depressed and to hold the locking member 39 in depressed position. In order to lock the transmission, the plunger 43 is pressed downwardly. The plunger pushes the locking member 39 into locking position, the latter being held in its depressed position by the projection 46 which engages an upper surface of the sliding head 40 of the locking member 39. A turn of the key 45 retracts the projection 46 and allows the spring 42 to push the member 39 upwardly into unlocked

position. In order to shut off the motor simultaneously with the locking of the transmission, I mount a contact member 47 on the member 39. A pair of points 48 are mounted on the side wall of the column 41 on each side of the path of the member 47. The points 48 are preferably connected in the ignition circuit and are so positioned that when the member 39 is in locking position, the contact member 47 is spaced from the points 48. When the member 39 rises to its unlocked position, the contact member 47 is thrust between the points 48 bridging these points and closing this portion of the ignition circuit.

It will be evident that by my invention an operator can simultaneously lock his car and shut off the engine by a turn of the key without touching his gear shift lever, so that the car may be locked in gear in any speed forward or reverse to which the transmission may be connected when the car is stopped or which the operator may select.

Having thus described an embodiment of my invention, it should be evident to those skilled in the art that many changes and modifications may be made therein without departing from its spirit or scope as defined by the appended claims.

I claim:

1. Locking mechanism for an automobile having shifter rods, a self-starter switch and an ignition circuit, comprising means for locking the shifter rods in any of their positions, means for locking the self-starter switch open, a normally closed switch in the ignition circuit, and a lock-controlled element actuatable to simultaneously move both of said locking means to locking position and open said ignition switch.

2. Apparatus of the class described, comprising a shaft, a cam plate mounted at one end of said shaft and inclined to the axis thereof, a locking lever engageable by said plate to be rocked thereby positively in either direction when said shaft is rotated, and a key-receiving lock-barrel actuatable to rotate said shaft.

3. In an automobile having an ignition circuit and a transmission mechanism including gear shifter rods, in combination, a member movable to lock said gear shifter rods selectively in any of their positions, and means for simultaneously moving said member to locking position and opening said ignition circuit.

4. Locking mechanism for an automobile having shifter rods, a self-starter switch and an ignition circuit, comprising a lever positioned to swing into engagement with said shifter rods in any of their positions and to hold said rods immovable, a lug projecting from said lever, a tilted cam disk having one face engaging said rod and its other face engaging said lug, a shaft secured to said cam

disk, a contact member carried by said shaft and movable therewith to open and close the ignition circuit, an ear on said shaft, a flexible element secured to said ear, means for locking said self-starter switch operatively attached to said flexible element, and a lock-barrel secured to said shaft to rotate there-

with whereby rotation of said lock-barrel in one direction simultaneously locks said shifter rods, opens said ignition circuit, and locks said self-starter switch. 10

In testimony whereof I have affixed my signature.

EDGAR J. MARTEL.
